CONTAINER LIFTER

Archie S. Krueger, Green Bay, Wis., assignor to
 Marathon Corporation, Rothschild, Wis., a corporation of Wisconsin

Application August 10, 1944, Serial No. 548,876

1 Claim. (Cl. 294—28)

This invention relates to container lifters and more particularly to a lifter for large paper containers used to package bulk ice cream.

The invention has as an object a lifter of the type referred to embodying a particularly simple and economical construction by which the lifter may be used to conveniently lift and carry containers.

The invention consists in the novel features and in the combinations and constructions hereinafter set forth and claimed.

In describing this invention, reference is had to the accompanying drawing in which like characters designate corresponding parts in all the views.

Figure 1 is a side, elevational view of a lifter embodying my invention.

Figure 2 represents a side elevation of the lifting device held in operative gripping relation to a container.

Figure 3 is a sectional view taken on lines 3—3 of Figure 1.

Figure 4 is a perspective view of the lifting device.

Figure 5 is a sectional view taken on lines 5—5 of Figure 4, and

Figure 6 is a view similar to Figure 5 while the lifting device is in gripping relation to a container.

Referring to the drawing, one form of the present invention consists of two oppositely disposed jaw members 10 and 11, the jaw member 10 being designated as a fixed jaw member and the jaw member 11 being designated as a pivoted jaw member. The jaw members are so mounted and arranged as to straddle the upper part of a can 5 or other article to be lifted, as shown in Figure 1. Preferably each of these jaws is formed from a flat strip of metal. The gripping end of the jaw member 10 is reversely bent to about a forty-five degree angle to provide a ledge 15 to seat under the neck bead of the can 5 for lifting purposes. The contact edge of this ledge 15 is preferably of saw-tooth shape to form a plurality of teeth 16 so disposed as to bite into the juxtaposed face of the can, this being a particularly advantageous construction where the can is made of paper. The gripping end of the jaw member 11 is likewise formed with a ledge 15 and teeth 16 for the same purpose. Fixed jaw member 11 is provided with an integral relatively long horizontally extending flat handle bar 25. Pivoted jaw member 10 is provided with an integral flat upper extension member 9 which normally aligns with handle bar 25, an integral downwardly extending portion

8, and an extending integral finger grip bar 12, terminating in an upwardly bent stop member 14.

A U-shaped bracket member 27 is spot welded at 30 to the portion 8, as shown in Figures 5 and 6. A pivot pin 40 extends through bracket 27 in freely rotatable relation thereto.

A U-shaped bracket member 26 is spot welded at 31 to the end of the flat handle bar member 25. The bracket is arranged to embrace bracket member 27 and is provided with openings 4 to fixedly receive pivot pin 40. A leaf spring 45 bent into U-shape is positioned within bracket member 27. One end of the leaf 50 contacts the finger grip bar 12 and normally urges the finger grip bar 12 to assume the position shown in Figures 1 and 5. The other end 51 of the leaf spring is positioned against the handle bar 25.

In operation the lifting device is held in the palm of the hand with the fingers grasping the finger grip bar 12 as shown in Figure 1. The lifting device is then positioned over a container 5 so that the teeth 16 of the fixed jaw member 11 engage a bead of the container 5. The finger grip bar 12 is then moved upwardly by the operator to assume the dotted line position shown in Figure 1. The pivoted jaw 10 will at the same time move toward the fixed jaw member 11 inwardly to the dotted position shown in Figure 1 and also as shown in Figures 2 and 6. In this position the teeth 16 of jaw member 10 will firmly grip the container which can then be lifted and carried in the manner illustrated in Figure 2. The weight of the container and the fingers of the operator serve to retain the finger grip bar 12 in its uppermost position, the end 20 of stop member abutting against handle bar 25. The container can be conveniently lifted and carried by one hand as the finger grip bar 12 and handle bar 25 are aligned and in parallel relation when stop member 14 abuts the handle bar 25. Upon release of grip bar 12, leaf spring 45 will automatically pivot grip bar 12 downwardly, whereupon the jaws will be released from the container.

The lifter described is of particularly economical and simple construction, being formed substantially from metal stampings, and the construction is such that the lifter is readily operated by one hand. While only a single form is shown in which this invention may be embodied, it is to be understood that the invention is not limited to any specific construction, but might be applied to various forms without departing from the spirit of the invention or the scope of the appended claims.

Having thus described the invention, what is claimed is:

A lifting device comprising a jaw member, a handle bar integral with said jaw member, a second jaw member pivoted to said handle bar, a finger grip bar integral with said pivoted jaw member and extending beneath said handle bar, a leaf spring interposed between one end of said handle bar and one end of said finger grip bar

for normally urging said finger grip bar into inoperative position, a stop member extending upwardly from one end of said finger grip bar to abut the said handle bar, said hinged jaw member being movable toward said jaw member upon moving said finger grip bar toward said handle bar.

ARCHIE S. KRUEGER.
